UNITED STATES PATENT OFFICE.

CALVIN B. PATCH, OF GLENELLYN, ILLINOIS, ASSIGNOR TO WILLIAM H. MINER, OF CHAZY, NEW YORK.

FRICITION-GEAR.

1,278,377.

Specification of Letters Patent. Patented Sept. 10, 1918.

Application filed September 8, 1916. Serial No. 118,971.

To all whom it may concern:

Be it known that I, CALVIN B. PATCH, a citizen of the United States, residing at Glenellyn, in the county of Dupage and State of Illinois, have invented a certain new and useful Improvement in Friction-Gears, of which the following is a full, clear, concise, and exact description, reference being had to the accompanying drawings, forming a part of this specification.

This invention relates to improvements in friction gears.

The object of the invention is to provide a relatively inexpensive friction gear for railway cars and wherein the friction shell may be readily renewed or replaced.

In the drawing forming a part of this specification, Figure 1 is a vertical, longitudinal section of a draft rigging showing my improvements in connection therewith. Fig. 2 is a horizontal sectional view of the structure illustrated in Fig. 1 and taken on the line 2—2 thereof. Fig. 3 is a vertical, transverse sectional view taken substantially on the line 3—3 of Fig. 1. And Fig. 4 is a detail sectional view illustrating a different type of yoke which may be employed with my invention.

In said drawing, 10—10 denote channel shaped center or draft sills between which are mounted the front upper and lower stops 11 and 12, respectively. The upper front stop 11 is riveted to the sills 10 by side flanges 13 and has a vertical stop shoulder 14 and horizontal web 15, the shoulder being suitably reinforced by ribs 16. The lower stop 12 is shown as secured to the lower flanges of the sills as by the rivets 17 and said stop is provided with a vertical shoulder 18 on its rear and a horizontal shelf or ledge 19 which forms a support for the butt of the draw bar 20.

The draw bar 20 is connected to the yoke A by means of a coupler key 21, the latter extending through suitable slots 22 in the front ends of the arms of the yoke and also through slots 23 in the sills. The normal position of the parts is shown in Fig. 2 where the coupler key 21 engages the rear of the slots 23 and is thus prevented from rearward movement. To reinforce the sills around the slots, plates or castings 24 may be riveted to the sills. It will be noted that

the slots 22 in the yoke are only slightly longer than the width of the key 21 so that the yoke A is prevented from rearward movement under buff. The yoke A, which is horizontally arranged, consists of side arms 25—25, the rear ends of which are bent inwardly and connected by a cross piece 26. Approximately centrally of the arms 25, the same are provided with slots 27, in which are received laterally extended lugs 28 formed integrally with a cylindrical friction shell 29. The lugs 28 fit snugly within the slots 27 and the shell is assembled with the yoke by springing the arms of the latter over said lugs. It will be noted that the shell 29 is relatively short, just sufficient to provide the necessary friction surface, and hence may be cheaply manufactured since it is formed with a minimum amount of material. Within the shell 29 is a circularly arranged set of friction shoes 30 with which co-operates a wedge 31, a plurality of anti-friction rollers 32 being interposed between the shoes and wedge. Within the shoes, at their rear ends, is mounted a washer 33 and the shoes engage an outer heavy spring 34 and an inner lighter spring 35, the rear ends of said springs bearing against the cross piece 26 of the yoke. A connecting bolt 36 extends from the wedge to the rear of the yoke and is thus adapted to hold the parts in assembled position and the springs under an initial compression. The wedge 31 engages the rear face of a front follower 37, the sides of said follower being notched or recessed as indicated at 38 to accommodate the side arms of the yoke. The cylinder 29 is supported by a saddle plate 39 which is detachably bolted to the lower flanges of the sills, said saddle plate 39 being extended upwardly at the center and provided with a curved bearing seat 40 to fit the underside of the cylinder. From the preceding, it will be seen that the shell is supported by the saddle plate and the shell in turn supports the yoke.

In the construction illustrated in Fig. 4, the arms 125, 125 of the yoke are made separate and are connected at their rear ends by means of a plate 126, the latter having rearwardly extended flanges 45 which are seated within corresponding grooves 46 formed at the rear of the yoke arms by upsetting

or bending the ends of the latter. The plate 126 is secured to the yoke arms by means of bolts 47.

In operation, under draft, the front follower 37 remains stationary and the yoke and shell move in unison with the draw bar, thus actuating the friction mechanism. Under buff, the yoke A is held stationary by the key 21 so that the friction shell is also held stationary. As the draw bar moves inwardly over the key 21, the front follower 37 is forced rearwardly, thus actuating the wedge and other elements of the friction mechanism.

15 Although I have herein shown and described what I now consider the preferred embodiment of the invention, the same is merely illustrative and I contemplate all changes that come within the scope of the 20 claims appended hereto.

I claim:

1. In a friction gear, the combination with front stops, of a follower coöperable with said stops, a horizontal yoke, means preventing rearward movement of said yoke under buff, a friction shell detachably but rigidly connected with said yoke and held thereby against rearward movement, friction elements coöperable with said shell, and a 30 spring within the yoke, the rear end of the spring being held by said yoke.

2. In a friction gear, the combination with a draw bar, front stops, a follower coöperating with said stops, of a horizontal yoke, a key connecting said yoke and draw bar, said key remaining stationary under buff and preventing rearward movement of the yoke, a friction shell detachably connected with said yoke and movable in unison therewith, the yoke preventing rearward movement of the shell, friction elements coöperable with said shell, and a spring, the yoke forming the rear stop for the spring.

3. In a friction gear, the combination with draft sills and front stop members, of a draw bar, a yoke, connections between the draw bar and yoke, the yoke being prevented from inward movement under buff and the draw bar being movable independently thereof under buff, a short friction shell detachably connected with said yoke and prevented from rearward movement by said yoke, friction elements coöperating with said shell, a follower coöperating with said stops, and spring means interposed between said

friction elements and the rear end of the yoke, the yoke acting as a rear stop for said spring.

4. In a draft rigging for railway cars, the combination with draft sills, a front follower, and stops for said follower, of a draw bar, a yoke, means for preventing rearward movement of said yoke under buff, connections between said draw bar and yoke arranged to move the yoke in unison with the draw bar in draft and permitting rearward movement of the draw bar independently of the yoke under buff, a short friction shell rigid with respect to the yoke and held stationary by the latter in buff, friction elements coöperable with said shell, and spring means interposed between said friction elements and the rear end of the yoke, the latter acting as a rear stop for said spring.

5. As an article of manufacture, a relatively short friction shell for friction draft riggings, said shell being open at each end and provided on its exterior at diametrically disposed points with radially extending lugs, said lugs being adapted to coöperate with openings in the yoke-acting member of the draft rigging.

6. In a draft rigging for railway cars, the combination with draft sills and a draw bar, of yoke-acting means including horizontally extending side arms, connecting means between said yoke-acting means and draw bar adapting the draw bar and yoke-acting means to move forwardly under draft in unison and permit the draw bar to move rearwardly under buff independently of the yoke-acting means, a relatively short friction shell detachably connected with said yoke-acting means and movable in unison therewith, friction elements coöperable with said shell, a member interposed between said friction elements and the rear end of the draw bar whereby pressure from the draw bar is transmitted to said friction elements, means for preventing forward movement of said member under draft, a spring interposed between said friction elements and the rear end of the yoke-acting means, and means for preventing rearward movement of said friction shell under draft.

In witness that I claim the foregoing I have hereunto subscribed my name this 5th day of Sept. 1916.

CALVIN B. PATCH.
